UNITED STATES PATENT OFFICE

ALEXANDER N. TEBIEFF, OF LOS ANGELES, CALIFORNIA

DESIGN FOR A SUGAR DISPENSER

Application filed May 27, 1929. Serial No. 31,428. Term of patent 7 years.

To all whom it may concern:

Be it known that I, ALEXANDER N. TEBIEFF, a citizen of Russia, residing at Los Angeles, in the county of Los Angeles and State of California, have invented a new, original, and ornamental Design for Sugar Dispensers, of which the following is a specification, reference being had to the accompanying drawing, forming a part thereof.

I claim:—

The ornamental design for a sugar dispenser substantially as shown.

ALEXANDER N. TEBIEFF.
